UNITED STATES PATENT OFFICE

128,696

DESIGN FOR A DRESS

David Armour, Larchmont, N. Y.

Application July 14, 1941, Serial No. 102,134

Term of patent 3½ years

To all whom it may concern:

Be it known that I, David Armour, citizen of the United States, residing in Larchmont, in the county of Westchester and State of New York, have invented a new, original, and ornamental Design for a Dress, of which the following is a specification, reference being had to the accompanying drawing, forming part thereof.

I claim:

The ornamental design for a dress, substantially as shown.

DAVID ARMOUR.
